UNITED STATES PATENT OFFICE.

THOMAS WASHINGTON CROZIER, OF ROANOKE, VIRGINIA.

DESIGN FOR A WINDOW-SASH LOCK.

SPECIFICATION forming part of Design No. 25,712, dated June 30, 1896.

Application filed April 28, 1896. Serial No. 589,462. Term of patent 14 years.

To all whom it may concern:

Be it known that I, THOMAS WASHINGTON CROZIER, a citizen of the United States, residing at Roanoke, in the county of Roanoke, 5 and State of Virginia, have invented a new and original Design for Window-Sash Locks, of which the following is a specification.

This invention relates to a new and original design for window-sash locks, and it has for 10 its object to provide a design of this character which shall be both useful and ornamental.

The leading feature of the design resides in a window-sash lock comprising two members 15 having inwardly-convergent outer side edges leading toward the joint between the two members, one of said members being of an approximate triangular form and having the peripheral and facial outlines of a bird with 20 outstretched wings, and the other member having a pair of spaced arms diverging outward to form a V-shaped figure and provided with outer rounded ends.

In the drawings, Figure 1 is a perspective 25 view of a window-sash lock embodying the herein-described design. Fig. 2 is a plan view thereof.

Referring to the accompanying drawings, the numeral 1 designates a window-sash lock comprising two members 2 and 3, having inwardly-convergent outer side edges 4 leading toward the joint 5 between the two members. The member 2 is of an approximate triangular form and is provided with the peripheral and facial outlines of a bird with outstretched wings, such as an owl, as illustrated in the drawings. The other member 3 is provided at its point of connection with the member 2 with a U-shaped portion 6, and is further provided with a pair of spaced arms 7, 35 diverging outward to form a V-shaped figure and provided with outer rounded ends 8 and lateral U-shaped projections 9 at such rounded ends.

What I claim is—

The design for a window-sash lock, herein 40 shown and described.

In testimony that I claim the foregoing as my own I have hereto affixed my signature in the presence of two witnesses.

THOMAS WASHINGTON CROZIER.

Witnesses:

R. GORDON SIMMONS,
T. F. BARKSDALE.
